UNITED STATES PATENT OFFICE.

FRED P. SMITH, OF WORCESTER, ASSIGNOR TO THE SMITH HEATING AND VENTILATING COMPANY, OF BOSTON, MASSACHUSETTS.

SYSTEM OF HOUSE VENTILATION.

SPECIFICATION forming part of Letters Patent No. 485,141, dated October 25, 1892.

Application filed April 22, 1892. Serial No. 430,183. (No model.)

To all whom it may concern:

Be it known that I, FRED P. SMITH, a citizen of the United States, residing at Worcester, in the county of Worcester and State of Massachusetts, have invented a new and useful System of House Ventilation, of which the following, together with the accompanying drawings, is a specification sufficiently full, clear, and exact to enable persons skilled in the art to which this invention appertains to make and use the same.

The object of my present invention is to afford a practical and convenient system of ventilation for homes, school-houses, churches, halls, and other public or private buildings, and to provide therein for the introduction of fresh warmed air at the ceiling or upper part and the withdrawal of vitiated air from the floor or lower part of the room in winter, and for the reversal of these conditions in summer; also, in a ventilating system to provide for the optional control and introduction of fresh air, warmed or cold, either at the ceiling or at the floor of the room, as may at any given time be desired; also, to afford in a system of ventilation facilities for the withdrawal of vitiated air from either the upper or lower portion of a room, and means for controlling or regulating the same at the option of the attendant. These objects I attain by the method and means herein illustrated and explained, the particular subject-matter claimed being hereinafter definitely specified.

In the drawings, Figure 1 is a vertical section of a ventilating air-conductor or ingress-flue illustrating my method of introducing the fresh air or warmed air to the room. Fig. 2 is a vertical section of a ventilating air-conductor or egress-flue, illustrating the withdrawal of vitiated air from the room, and Fig. 3 is a perspective sectional view illustrating the arrangement of the ingress and egress flues, their registers, and valves.

In carrying out my improvement the building is provided with separate ingress and egress flues or ducts for each room. These flues are each provided with two separate openings or registers respectively located one at or near the ceiling or communicating with the upper part of the room and the other at or near the floor or communicating with

the lower part of the room. A stop gate or valve is arranged within the flue and adapted in suitable manner for controlling the flow of the air-current and cause the same to pass either through the upper register or opening or through the lower register or opening at the option or pleasure of the attendant and by the shifting of the valve or gate.

Referring to parts, A and A' denote rooms to be ventilated, which may be school-rooms, halls, offices, chambers, or any other building apart.

B B' and b b' denote the several floors and ceilings of the rooms.

D indicates the ingress-flue or air-shaft, leading from the source of fresh-air supply or from the heating apparatus H, whereby warmed fresh air is conducted to the apartment, and E indicates the egress-flue or air-shaft, by way of which the vitiated air is withdrawn or conducted away from the apartment and up through the stack.

The delivery-openings from the flue D into the room A are indicated at d and d', and the exit-openings from the room A to the flue E are indicated at e and e'. These openings in the wall of the room are in practice best provided with suitable grills or ornamental guards, as desired; but said grills have been omitted from the drawing Fig. 3 for simplifying the illustration.

F indicates the stop gate or valve arranged in the ingress-flue D, preferably just above the lower opening d, and adapted to swing backward for closing the flue-passage and opening the register d for delivery of air therethrough or to swing forward for closing the register-opening d and opening the flue-passage, so that the air will deliver through the register d'.

G indicates the stop gate or valve arranged in the egress-flue E, preferably just below the upper opening e, and adapted for closing said opening e and affording unobstructed passage through the flue from the lower register e' when in forward position or to swing backward, so as to open the upper register or space e and to close the flue-passage from the lower register e'. Said valves F and G are provided with handles m or any convenient means for effecting their operation and adjustment to

forward or backward position or to any intermediate inclination between their limits of movement.

In buildings of several stories the ingress-flue for the lower room A' can where convenient be a portion of the same structure as the egress-flue from the upper room A, a separating-partition I being built across the interior at the floor-line, as shown in Figs. 2 and 3.

10 In Fig. 1 there is shown the arrangement of a heater H or means for warming and delivering fresh air to the room A either at the floor or ceiling, and in Fig. 2 there is shown the arrangement of means for withdrawing

15 vitiated air from the room A either at the floor or ceiling. These ingress and egress appliances can in some cases be employed separately, if desired, but are preferably employed together and as illustrated in Fig. 3. The

20 flues or passages for both ingress and egress of air are best at the same side of the room and at the side opposite the windows. The circulation of air may be induced by mechanically-forced blast or exhaust action or in other 25 instances by natural draft or a current movement induced by variation of temperature.

By the improvement herein described a system of ventilation is afforded whereby warmed fresh air can in winter be introduced

30 at d at the ceiling or upper part of the room and the cooled or vitiated air withdrawn at e at the floor or lower part of the room, thus in an efficient and practical manner meeting the requirements and conditions of

35 cold-weather heating and ventilating. Then for summer, without change other than the shifting of the valves F and G, the fresh air can be introduced at d' at the floor and the vitiated air withdrawn at e' at the ceiling,

40 thus in equally-efficient manner meeting the conditions and requirements of warm-weather ventilation. This system is by my improvement also rendered controllable at the will of the attendant for the varying conditions and

45 circumstances of climatic changes of temperature and different exposures of the various rooms or for quickly changing the quality of air or the degree of temperature in any room.

50 I claim as my invention herein, to be secured by Letters Patent—

1. In a system of house ventilation, an ingress-flue or air-duct having an opening for delivering air into the room at or near the

ceiling and another opening for delivering 55 air into the room at or near the floor and a stop gate or valve disposed within said flue and controlling the passage for directing the air-current for delivery through either said upper or said lower opening, substantially as 60 set forth.

2. In the system of house ventilation, the egress-flue or air-duct having an opening thereinto from the room at or near the floor and another opening from the room at or near 65 the ceiling and a stop gate or valve disposed within said flue adjacent to said upper opening and adapted for closing the same and opening the flue below or to swing back, obstructing the flue from the lower opening and permitting air to pass through said upper opening, substantially as and for the purpose set forth.

3. In a system of house ventilation, the combination, with the apartment or room, of 75 the ingress-flue having two openings for the delivery of air into said room, respectively located one at the upper and the other at the lower part of the room, and a cut-off or valve controlling the delivery of air through either 80 one or the other of said openings, the egress-flue provided with an upper opening and a lower opening, respectively located at or near the ceiling and floor of the room, and a cut-off or valve controlling the passage to afford 85 exit of air through either one or the other of said openings, and means for operating said valves to change the delivery and exit to either upper or lower positions, substantially 90 as and for the purpose set forth.

4. The combination of the ingress-flue having the upper and lower openings or air-delivery registers, the hinged cut-off valve arranged therein to swing over said lower opening and backward across the ingress-flue, the 95 egress-flue having the upper and lower openings or air-exit registers, the hinged cut-off valve arranged therein to swing over said upper opening and backward across said egress-flue, and valve-operating devices whereby an 100 attendant can adjust said valves at any desired position, for the purposes set forth.

Witness my hand this 13th day of April, A. D. 1892.

FRED P. SMITH.
